UNITED STATES PATENT OFFICE

2,070,517

APPARATUS FOR DISPENSING LIQUIDS

Eugene A. O'Leary, Holyoke, Mass., assignor to
Arthur E. O'Leary, Holyoke, Mass.

Application March 25, 1936, Serial No. 70,808

4 Claims. (Cl. 225—3)

This invention relates to improvements in apparatus for dispensing liquids such as disclosed in U. S. Letters Patent No. 2,032,095 granted to me February 25, 1936.

5 The principal objects of the invention are directed to the provision of an apparatus for dispensing liquids of all kinds and may be used advantageously for dispensing beverages such as beer or the like.

10 The apparatus is so constructed and arranged that it may be associated with a container and according to its novel construction air or other fluids may be delivered to the container to force the contents upwardly through the apparatus and system to which it is connected and at the same time means is provided whereby the apparatus may be cleaned by passing some cleaning fluid through the said apparatus and system.

15 Various other novel features and advantages 20 of the invention will be hereinafter referred to in connection with the accompanying description of the preferred form thereof, reference being had to the accompanying drawing wherein:

Fig. 1 is a partial elevational and sectional view of an apparatus embodying the novel features of the invention;

Fig. 2 is a sectional view on the line 2—2 of Fig. 1;

Fig. 3 is a sectional view showing certain of 30 the parts illustrated in Fig. 1; and

Fig. 4 is a sectional view on the line 4—4 of Fig. 2.

Referring now to the drawing more in detail, the invention will be fully described.

35 A body is represented at 2 which has an internally threaded bore 4 adapted to receive a coupling. To such a coupling there may be attached a pipe or conduit for conducting air or other fluid to the body 2.

40 A valve member 8 is rotatable in the body 2 and is preferably in the form of a tapered valve which fits into a tapering bore as shown in Fig. 2. Tension means in the form of a spring 10 is disposed at one end of the plug 8 and a nut 12 is in threaded engagement with the end of the plug. This is arranged to bear on the spring so that the valve member 8 is urged into proper seating engagement with its bore.

45 A handle 14 is associated with the plug 8 and a stop pin 16 associated with the plug is adapted to abut a stop or stops such as 18 provided on the body. In this way rotative movements of the plug are limited.

50 There is a chamber 24 in the lower part of the body 2 which is closed by a plug 26 having an

internal screw-threaded portion 28. A boss 34 in the chamber 24 carries a check-valve member 36 which is preferably of some resilient material such as rubber or the like and has an opening or slot therethrough. The check valve 34 is arranged to allow fluid to pass downwardly therethrough but prevents the passage thereof in an opposite direction.

An outer tube member 50 extends downwardly from a chamber 52 provided in body 2 below valve 10 8 which is in communication with chamber 24 by means of a passageway 54. A passageway 57 extends upwardly from chamber 52 to the valve 8.

An inner tube 58 extends downwardly within the outer tube 50 and is in communication with passageway 57, while a cap member 60 is in screw-threaded engagement with the lower ends of both tube 50 and tube 58, as shown in Fig. 3. One or more openings such as 62 extend through the wall of the cap 60 and lead into tube 58 while an opening 64 is provided in the wall of the tube 50 intermediate its ends which leads into the space between the tubes 50 and 58.

According to the preferred form of the invention, a clean-out plug 64 is provided in the lower 25 end of cap 60 to permit cleaning of tube 58. The plug 64 may or may not be screw-threaded.

The body 2 is provided with a chamber 15 and therein is a check-valve member 13, similar to the member 36, which is disposed on the inner 30 end of a hollow plug 11. The hollow plug 11 extends into bore 4 and may be screw-threaded into the body, as shown.

An opening 40 extends transversely through the plug 8 and another opening 42 leads from one 35 side of the plug to said opening 40, as shown in Figs. 2 and 4. When the plug 8 is in the position shown, it brings passageways 40 and 57 into communication while when it is rotated to its other intended position, the passageway 42 is in communication with passageway 38 and hence chamber 15, as will appear.

A threaded part 44 for a coupling is provided on the upper side of the body 2 to which a conduit or delivery pipe may be connected and 45 which may extend a considerable distance to the place where the liquid is to be dispensed, such as a bar. In the ordinary case there will be a faucet controlling the outlet of such a conduit. A passageway 45 extends downwardly through 50 part 44 to the valve 8 so that, as shown in Fig. 4, communication may be had between passageways 57 and the delivery pipe.

A plug 17 having an end projection 19 for a hose or the like has a threaded part 21 screwed 55.

into the body 2, as shown in Fig. 2. This plug 17 is hollow and has a check valve 23 on its end which is similar to the valves 13 and 36. This valve 23 is disposed in a chamber 25 provided in the body and there is a passageway 27 leading from said chamber 25 to chamber 15.

The apparatus may be employed for various purposes but it is particularly useful in connection with the dispensing of beverages such as beer. In such a case, the tube 50 is inserted in the container of the beer, such as a keg, so that the lower end of the tube or cap is adjacent the lower side of the container. As stated, a pipe extends from the threaded outlet part 44 to the place where the beer is to be dispensed and will have at its upper end a faucet or spigot to control the flow of the beer.

The bore 4 may be connected to an air supply, such as a compressor or the like. With the valve 20 plug 8 in the position shown it will be readily seen that the horizontal passageway 30 is cut off from the vertical passageways 45 and 57.

In this way when air is delivered through bore 4 it passes downwardly through passageway 32, 25 through check-valve 36, inwardly through passageway 54, and then downwardly between the inner tube 58 and outer tube 50 to pass out the opening or openings 64' in the tube 50 and into the container. With the air thus admitted into 30 the container, the beer of the container is caused to flow through the opening or openings 62 and thence upwardly through inner tube 58, and through passageways 57, 40 and 45 and out part 44 so that the beer is forced through the system connected to part 44 to the point where it is dispensed.

In the dispensing of beverages such as beer and the like, it is necessary to clean the system frequently. It is common practice to force air, 40 water or other cleaning fluid through the system by disconnecting the conduit at the container. This has many disadvantages however in that the beer in the system is wasted.

According to this invention, it is possible to 45 clean the system leading from the part 44 in a very short time. This is accomplished in the following manner.

The valve 8 is rotated so passageway 40 thereof aligns with passageway 30. Water or other 50 cleaning fluid is admitted through fitting 17, past check-valve 23, through passageway 27 and into chamber 15. It then passes through passageways 30 and 40 and then upwardly through passageways 42 and 45 into the system.

The fluid cannot, by reason of check-valve 13, 55 pass into the air pipe nor downwardly through tube 50. Also with the valve 8 in the position just referred to air may be delivered into chamber 15 and will force beer in the system therefrom so that it is not wasted. This will be desirable before the cleaning fluid is used.

What I desire to claim and secure by Letters Patent of the United States is:

1. An apparatus for dispensing beverages comprising in combination, a body having an outlet and provided with a pair of chambers in com-

munication with one another, each having an inlet, and a third chamber in communication with the inlet of one of the pair of chambers, an outer tube member in communication with said third chamber, an inner tube within said outer tube, and a valve rotatable in said body, the said body and valve being provided with passageways whereby the valve may be positioned to direct fluid entering said one of the pair of chambers to either said outlet or said third chamber and thence to the outer tube. 10

2. An apparatus for dispensing beverages comprising in combination, a body having an outlet and provided with one chamber having an inlet and a second chamber having an inlet and a third chamber, the said second chamber being in communication with the first-named chamber and the said third chamber being in communication with the inlet of the first chamber, an outer tube in communication with said third chamber, an inner tube within said outer tube, and a valve rotatable in said body, the said body and valve being provided with passageways whereby the valve may be positioned to direct fluid entering said inlet of the first-named chamber either to said outlet in the body or to said third chamber and thence to said outer tube. 25

3. An apparatus for dispensing beverages comprising in combination, a body having an outlet and provided with a pair of chambers in communication with one another, each having an inlet, and a third chamber in communication with the inlet of one of the pair of chambers, an outer vertically disposed tube in communication with said third chamber, an inner tube disposed within said outer tube, a unitary cap member in screw-threaded engagement with the lower ends of both of said tubes, the said lower end of the inner tube and said cap member being provided with openings, and a valve rotatable in said body, 40 the said body and valve being provided with passageways whereby the valve may be positioned to direct fluid entering said one of the pair of chambers to either said outlet or said third chamber and thence to the outer tube. 45

4. An apparatus for dispensing beverages comprising in combination, a body having an outlet and provided with a pair of chambers in communication with one another, each having an inlet, a third chamber in communication with the inlet of one of the pair of chambers, an outer vertically disposed tube in communication with said third chamber, an inner tube disposed within said outer tube, a unitary cap member in screw-threaded engagement with the lower ends of both of said tubes, the said lower end of the inner tube and said cap member being provided with openings, a valve rotatable in said body, the said body and valve being provided with passageways whereby the valve may be positioned to direct fluid entering said one of the pair of chambers to either said outlet or said third chamber and thence to the outer tube, and a clean-out plug removably associated with said cap member. 50
